2 SHEETS - SHEET 2.

UNITED STATES PATENT OFFICE.

ODO RUZSICKA, OF NEWARK, NEW JERSEY, ASSIGNOR OF ONE-SIXTH TO HENRY LIEFERANT AND ONE-SIXTH TO SAM BUSCH, BOTH OF NEWARK, NEW JERSEY.

VENDING-MACHINE.

1,181,547.

Specification of Letters Patent.

Patented May 2, 1916.

Application filed December 6, 1915. Serial No. 65,190.

To all whom it may concern:

Be it known that I, Odo RUZSICKA, a citizen of the United States, and a resident of Newark, county of Essex, and State of New Jersey, have invented certain new and useful Improvements in Vending-Machines, of which the following is a specification.

This invention relates to a vending machine for dispensing articles when a coin is deposited in the machine, the machine delivering the article when the coin has been deposited and no further manipulation of the machine is necessary beyond the positive insertion of the coin in the slot.

15 The invention is adapted for many sizes and for different articles, but is principally designed for use in small machines, such as machines that will deliver chewing gum and like packages, and is adapted for use in trolley cars and similar conveyances, the machine not being apt to be injured by any swaying or movement of the car, occupies but a small space so that it can be easily installed between windows of cars, and does 25 not project sufficiently to interfere with the view or comfort of any of the passengers, the machine at the same time being handy for use.

This invention further provides a machine 20 of this kind in which the chute for holding the goods is easily installed and detached so that if necessary a filled chute can be easily placed in the machine in lieu of an empty one, thus saving time, this being important 25 where machines on cars are to be filled and it would be objectionable to have any considerable time used for such purpose.

This machine is also designed to provide an outlet which presents the gum or other 20 article vended so that it can be easily withdrawn from the machine, but there are no trays or other projecting parts to catch on the clothing or have similar objectionable 25 features, also preventing the accumulation of dust.

A further object of the invention is to provide a machine of this kind in which any coin smaller in diameter than the coin for which the machine is designed, will be received into the machine, but the machine will not deliver an article, and similarly, a coin lighter in weight than the required coin will not operate the releasing mechanism of the articles sold.

55 Another object of the invention is to pro-

vide a means for preventing the insertion of iron or steel disks or slugs, these iron or steel disks acting magnetically on the stopping device which positively prevents the insertion of such slug any material distance 60 into the machine.

Another object of the invention is to provide the closing of the slot through which coins are inserted when the supply of articles in the machine is exhausted.

65 The invention is illustrated in the accompanying drawings, in which—

Figure 1 is a face view of the machine with an article delivered ready for removal from the machine. Fig. 2 is a side view, 70 but with the casing of the machine shown in section so as to illustrate the interior mechanism in elevation. Fig. 3 is a perspective view of one side and the back of the chute and its attached parts. Fig. 4 is a section 75 through the chute showing how the goods are held and delivered. Fig. 5 is a horizontal section approximately on line 5—5 in Fig. 1, and illustrating the relation of the coin slot and the guide for the coin as it is 80 passing through the slot. Fig. 6 is a perspective view of a weight that is deposited on the machine and which operates to release the slot-closing means, and Fig. 7 is a 85 detail view showing the manner in which a slug made of metal, affected by magnetism, is held from any material entrance into the machine.

The machine is preferably installed so that it can be securely fastened in place against 90 thievery, but its construction is such that it has ready means for removing the chute carrying part from the back plate, and in turn it has means for easily removing the back of the chute carrying part to uncover 95 the device and permit its inspection and supply.

In the form shown, the supporting plate 10 is secured to the wall, post or other element on which the machine is to be secured, the supporting plate 10 being usually fastened by passing screws through holes in it, and it is provided with means for removably holding the casing on the machine, such means in the machine illustrated consisting of headed studs 11, behind the heads of which pass the slots 12 in a back plate 13 of the casing, the casing having a front plate 14, sides 15 and a top 16. The top 16 is provided with slots into which the fin-

gers 17 pass, and a lock 18 has a tongue 19 which fits into the slot 20, the fingers 17 and the tongue 19 acting to hold the casing against the back plate 13, the back plate 13 being in turn held by the before-mentioned studs 11 and also by a tongue 21 of the lock 22, which tongue is operated by means of a suitable key which is inserted through the usual slot 23 in the lock 22. The lock 18 has a key-receiving part that is arranged so that it projects from the back of the back plate 13, as at 24 in Fig. 2, so that the lock is not in sight nor available for operation until after the back plate 13 has been removed from the supporting plate 10, as will be evident. When a machine is to be renewed and it is to be done in a hurry so as to prevent the counting of coin and the insertion of articles while the machine is in place, a filled machine supported, as will be hereinafter described, within the casing and on the back plate 13, can be quickly placed on a supporting plate 10 by passing it over the studs 11 and locking it at the top, in the form shown this being done by means of the tongue 21 of the lock 22. When the machine is empty, it can be removed by unlocking the lock 22 and slipping the back plate over the studs 11 and a filled machine quickly inserted in its place as above described. When the casing is to have its coin removed or to have articles installed therein, the lock 18 is operated to withdraw the tongue 19, and the casing, which is preferably made of sheet metal, can be lifted from the fingers 17 and the operating mechanism of the device is accessible, the chute can be easily filled with articles and coins taken from the casing without any difficulty.

The chute 25 has any suitable means for supporting it on the back plate 13, the form shown consisting of the brackets 26 which are fastened by the screws 27 to the back plate 13, and a plate 28 secured by a screw 29 to the back plate 13. The screw 29 passes through a hole 30 in the clamping plate 31, which is held by means of a screw 32 so that it tightly grasps the end of a spring 33, the spring extending downward and bearing against the back of a lever 34 which is pivoted as at 34^a, preferably at the bottom part of the plate 28, the bottom end of which is bent upward as at 35 and extends into the bottom part of the inside of the chute 25, this end 35 being preferably inclined to a considerable extent and acting to support the articles or packages 36, these being usually made to approximately fit the chute, the chute and articles in this particular machine that is illustrated being made oblong. The chute comprises the back 37 against which the lever 34 normally rests, sides 38 and front pieces 39 which have an opening 40 between them so that

the placing of articles in the machine is convenient and easy. The chute also contains a follower 41 which insures the descent of the articles and also makes it positive that the lowermost article is put into delivering position when the lever 34 is pulled back. The lever 34 has a nose 42 which extends around to the side of the chute 25 and has its rounded end 43 arranged opposite the slot 44 in the front plate 14 of the casing. When a coin 45 is pushed into the slot 44 it engages the bottom edge 46 of the slot and also the rounded part 43 of the nose 42 and the lever 34 is swung backward so that it has its bottom part 35 pushed back to the position shown in dotted lines in Fig. 4. If the coin is of the desired size, that is, of the size for which the machine is designed, the lever 34 is pushed back far enough so that the forward end 47 of the bottom part 35 passes beyond the back of the lowermost package 36, as shown in dotted outline at 48 in Fig. 4. This permits the lowermost of the packages to drop to the dotted position on the ends 86 of the bottom of the chute as shown at 49 in said figure, the lever 34, however, being held back in this position, at least momentarily, by reason of a pivoted ratchet 50 which swings on the pivot 51 at the side of the chute and has teeth 52 thereon, the lever when in the rearmost position shown in Fig. 4 being held by the last tooth 53 which engages the bottom of the slot 54 in the extension 55 of the lever 34, the bottom of the slot 54 being preferably tapered so as to pass in between the teeth 52 with ease. When said lever 34 is held by the tooth 53 and the lowermost package in the position shown at 49, the coin has been forced downward by reason of the curved surface 43 engaging it and the coin is guided in its descent by the shelf 56 and the coin chute 57. Underneath the coin chute and secured to the arm 58 of the ratchet 50 is a plate 59, and when the coin hits the plate 59, this plate, the arm 58 and the ratchet 50 all act as a trip, the rack is thrown upward with a sharp jerk and the spring 33 is allowed to press or snap the lever 34 forward, which pushes the article in the position 49 in Fig. 4 out between the side wings 60 of the chute and the article falls down between said wings 60 and the bottom 61 of the delivery tray 62 and it is thus directed to the slot 63. The slot 63 is narrower than the package is long, and it has a supporting finger 64 which holds one end of the package as at 65, and one end 66 of the package is thus permitted to project a substantial distance from the slot 63, but it does not drop out, and if grasped and slightly turned, it can be easily withdrawn. The narrow slot, with its function of tilting the article at its delivery point and allowing a part of it to project 130

but still holding it from falling, overcomes the necessity of a delivery tray which has some disadvantages, such as undue projection and the catching of dust and dirt.

enter the chute to be an obstruction therein and must be withdrawn. This effectually prevents fraudulent extraction of goods by means of steel or iron slugs made the same size as the coin for which the machine is 70 designed.

To prevent the insertion of coins into the machine when the machine has been emptied of goods, I provide a device which is operated by the follower 41 and consists of a 75 right-angled lever, the lower arm 74 of which is pivoted at 75 and has an upper edge 76 that is so disposed that it is in the path of travel of the lip 77 of the follower 41, and when the lip 77 hits the end 78 it 80 is when the last of the packages 36 is expelled and the follower drops, carrying the arm 74 with it, and thus swinging the upright arm 78 of the right-angled lever so that the pin 79 is withdrawn from a perforation 80 in the flanged end 81 of a closure plate 82, the closure plate when released 85 swinging downward by its own weight on the pivotal pin 83 which is preferably a screw with its head slightly removed from 90 the face of one of the sides 39 of the chute 25. When so swung, the edge 84 of the closure plate 82 swings beyond the edge of the slot 44 and the slot is closed. The closure plate 82 is preferably arranged so that it 95 can be removed to permit the ready filling of the chute with packages of goods to be sold, and to provide for the easy removal and installation of the closure plate it is usually made with a slot having tapered 100 edges 85, the slot being arranged to project upwardly into the plate, the tapered edge of the slot providing for its quick installation, and the closure plate is then held so that the pin 79 can be placed into the hole 105 80 and the device is set.

The above description and illustration to which it applies show an embodiment of the invention that operates successfully, but it will be evident that changes can be made 110 in this construction and the proportions and dispositions of the parts without departing from the invention, and I do not wish to be limited to the exact construction illustrated.

The lever 34 is held back in its preparatory or expelling position by the rack 50, or its equivalent, so as to prevent any swinging of the lever back and forth. This prevents such swinging by a pin or wire bearing on the nose 42, since if no stop for the 120 lever were provided, it could eject the lowest article 36. The plate 56 is placed so that no tripping of the plate 59 can be done by a hatpin or similar implement inserted through the slot 44.

In this machine the expelling device, which is placed in position when a coin is inserted and later released or tripped by the same coin so that an article is expelled or delivered, is conveniently arranged and is 130

5 The bottom package is projected from its place by reason of the turned or flanged part 47 of the bottom 35 of the lever 34. The package above the bottom package, when the bottom package is in the position 10 shown at 49, is prevented from being propelled forward by reason of the strip 67 which projects across the lower part of the slot 40. To guide the coin 45 as it passes through the coin slot 44 and engages the 15 end 43 of the nose 42, I provide a guide which prevents tilting of the coin and directs it, said guide having an upper projecting part 68 which lies close against the side of the slot and prevents the coin from 20 riding upward at that point, the part 68^a being in line with the end 43 of the nose, and a lower projecting part 69^a which is to one side of the end 43 and prevents tilting of the coin while it is in engagement with 25 the end 43. If a coin is too small to force the lever 34 back far enough to engage the last tooth 53, the bottom 35 of the lever 34 is not pulled back far enough to put it in ejecting position, but if a slug of very light 30 weight and of the proper diameter is inserted in the slot, and the lever 34 is pushed back far enough, the weight of the coin, when it descends and hits the plate 59, is not sufficient to trip the lever 34 to eject 35 a package. The removal of such a released package, however, that could be ejected if the plate 59 was tripped, is impossible by means of a wire inserted through the slot 63, as the bottom 61 of the tray 62 acts as 40 a shield to prevent the engagement thereof by means of a pin or long needle through the slot. The tripping plate 59 cannot be operated through the slot 63 on account of one of the wings 60 shielding it from access 45 through the slot.

Adjacent to the slot I have suspended a magnet so that it can swing to the desired extent, the form shown consisting of a magnet 68 pivoted by means of a pivotal pin or 50 screw 69 to a block 70, the poles of the magnet being arranged opposite the slot 44, and if a steel or iron or any other slug that is affected by magnetism, is inserted in the slot, the coin being held by the slot against 55 side movement, attracts the magnet and interferes with its ready insertion. If, however, the slug is pushed in an attempt to pass it by the magnet, the coin engages a suitable pin or screw 71 which, when the 60 magnet is drawn toward the chute by the slug 72, projects a slight distance into a recess or hole 73 in the side of the chute 25, and it is impossible to force the slug in engagement with the mechanism for setting 65 the expelling device, and the coin cannot

compact to permit the major portion of the machine to be utilized for articles on sale.

Having thus described my invention, I claim:

5. 1. A vending machine comprising a stationary article chute, a lever fulcrumed close to the side of said chute and provided with a lateral extension normally serving as a support for articles in the chute, means on the lever between the extension and its point of fulcruming, whereby it may be swung by an inserted coin into a non-supporting position, means for releasably holding said lever in the last-named position, and means in the path of the coin for releasing said holding means.
10. 2. A vending machine comprising a stationary article chute, a lever pivoted close to the chute near its upper end and having an extension to extend below said chute, means actuated by the insertion of a coin for swinging said lever on its pivot into a non-supporting position, means for releasably holding said lever in the last-named position, and means in the path of the coin for releasing said holding means.
15. 3. A vending machine comprising a stationary article chute, a lever provided with a lateral extension normally serving as a support for articles in the chute, means on the lever between the extension and its point of fulcruming, whereby it may be swung by an inserted coin into a non-supporting position, means for releasably holding said lever in the last-named position, and means in the path of the coin for releasing said holding means.
20. 4. A vending machine comprising a chute having means on the bottom for supporting a column of articles, the bottom having an opening therein, a lever with a bottom portion in said opening, said bottom being constructed so that it supports the column of articles above the bottom of the chute, means for engagement with an inserted coin for moving the lever so that it does not support the articles, a holding means for retaining said lever in various positions, tripping means connected with the holding means, said tripping means being adapted to be actuated by a coin, and means for forcing said lever to its normal position when the tripping means is operated.
25. 5. A vending machine comprising a chute having means in the bottom thereof for supporting a column of articles, a swinging lever having its bottom portion arranged in the chute and adapted to support the column of articles above the bottom of the chute, means on said lever adapted to be actuated by a coin whereby the lever is swung to permit the column of articles to be dropped so that the bottom article is in the path of travel of the lever, a holding and tripping means in engagement with the

lever and adapted to be actuated by a coin subsequent to the movement of the lever by said coin, and means for moving the lever to its normal position when it is tripped.

6. A vending machine comprising a chute 70 for holding a column of articles, a lever having its end adapted to enter the chute and support the articles above the bottom of the chute, the chute having means for supporting the articles when the lever is withdrawn, means attached to the lever for withdrawing it from the chute by the insertion of a coin into the machine, said lever when withdrawn permitting the dropping of the packages so as to place one of the articles 80 to be expelled in the path of travel of the lever, a ratchet adapted to hold said lever in its withdrawn position, means on said ratchet adapted to be engaged by the coin for tripping the ratchet, and a spring for 85 returning the lever to its normal position when the ratchet is tripped, said lever on its return ejecting the article in its path of travel and then supporting the column of articles.

7. A vending machine comprising a chute having means therein for supporting a column of articles, a lever pivotally supported on the back of the chute and having a nose extending around the side of the chute, a casing with a coin slot therein opposite the nose whereby the insertion of a coin moves said nose and the lever, the lever having a bottom portion thereon which normally supports the column of articles above the support in 100 the chute, said bottom portion when the lever is withdrawn releasing said column of articles and taking a position so that one of said articles is in its path of travel when it returns to its normal position, a ratchet pivoted on the side of said chute and adapted to engage the lever to hold the lever in its withdrawn position, a tripping means on said ratchet to move the ratchet so as to release the lever, a spring for moving said lever to its normal position when it is released, and means for conducting a coin after it passes the nose and directing it to the tripping mechanism, said coin directing means being so disposed so that it prevents the 115 passage of a straight implement from the coin slot to said tripping means.

8. A vending machine comprising a chute having means therein for supporting a column of articles, a lever pivotally supported 120 on the back of the chute and having a nose extending around the side of the chute, a casing with a coin slot therein opposite the nose whereby the insertion of a coin moves said nose and the lever, the lever having a 125 bottom portion thereon which normally supports the column of articles above the support in the chute, said bottom portion when the lever is withdrawn releasing said column of articles and taking a position so that 130

one of said articles is in its path of travel when it returns to its normal position, a ratchet pivoted on the side of said chute and adapted to engage the lever to hold the lever 5 in its withdrawn position, a tripping means on said ratchet to move the ratchet so as to release the lever, a spring for moving said lever to its normal position when it is released, means for conducting a coin after it 10 passes the nose and directing it to the tripping mechanism, said coin directing means being so disposed so that it prevents the passage of a straight implement from the coin slot to said tripping means, a delivery tray 15 having side wings, and a slot in the casing at the bottom of the tray, said tray having its delivery surface bent so as to form a projecting part between the slot and the column of articles.

20 9. A vending machine comprising a chute for supporting a column of articles to be vended, the chute having means on the bottom thereof for supporting said column, a lever pivoted to the back of the chute and 25 having a bottom portion to extend into the chute, said bottom of the lever supporting the column of articles above the bottom of the chute, the lever having a nose at the side of the chute, a casing having a coin slot 30 therein, the slot being disposed so that a coin when forced between the edge of the slot and the nose of the lever forces the lever to be withdrawn from the position where it supports the column of articles, the articles 35 when so released dropping to place one of said articles in the path of travel of the lever when said lever swings to its normal position, coin guides adjacent to said nose to prevent tilting of the coin, an extension 40 on the lever, a right-angled ratchet pivoted at the side of the chute, said ratchet being adapted to engage the extension of the lever to hold the lever in its withdrawn position, a plate on the ratchet adapted to receive a 45 coin subsequent to the operation of the lever

by said coin so that the ratchet is tripped, a spring to force the lever to its normal position when released from the ratchet, coin directing means between the nose and the tripping means, said coin directing means 50 causing the coin to travel in a circuitous route, and a delivery tray having a bent portion therein, the casing having a slot below the bent portion whereby an article passing down the tray is directed to the slot, the 55 bent portion of the tray preventing access by a straight implement through the slot to the column of articles.

10. A vending machine comprising a stationary article chute, a spring-pressed lever pivoted at its upper end to one side of the chute, said lever lying against the chute whereby its swinging movement is limited by the chute, the lever having a lateral extension normally serving as a support for 60 articles in the chute, and means on the lever disposed so that an inserted coin swings the lever so that it does not engage the chute and permits the articles in the chute to drop.

11. A vending machine comprising a stationary article chute, a lever fulcrumed at its top end to one side of the chute, a spring bearing on the lever and pressing it toward the chute, the chute acting to limit the swinging of the lever when it is actuated by 70 the spring, the chute having an opening in its bottom, the lever having a lateral extension extending into the chute when the lever engages the chute, said extension supporting the articles in the chute when in such position, and means on the lever whereby said means, when engaged by an inserted coin, 75 swings the lever from engagement with the chute and withdraws its support from the articles in the chute.

In testimony that I claim the foregoing, I hereto set my hand, this 2nd day of December, 1915.

ODO RUZSICSKA.
